UNITED STATES PATENT OFFICE

AUGUST W. SCHMID, OF CONNERSVILLE, INDIANA

PULL-TIGHT MOLDING

Application filed January 8, 1929. Serial No. 331,121.

This invention relates to an improvement in moldings, trimmings, welts and similar articles, where concealed attaching devices, such as nails or tacks, are employed.

The object of this invention is to devise a construction where the attaching devices can be most readily applied and thereafter be securely and readily concealed. It is manifestly desirable that any folding part of the 50 welt or molding, which is utilized for folding over the attaching device and concealing same, should occupy an initial position such that the attaching device can most readily be applied and yet in a closed or final position should be most readily and securely held in that final position. To that end it is desirable that the parts be, in the closed position and in the initial position, as flexible and mobile as consistent with their final 55 holding action and at the same time it is desirable to eliminate all adhesives that may deteriorate and yet have a locking effect as positive as possible without requiring too accurate construction of parts.

This improved trimming or molding meets all the foregoing requirements, and is one that requires no special tool for the finishing operation but can be manipulated in a most satisfactory manner at all times and for all 60 conditions of use.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout.

In the drawings Figure 1 is a top plan view showing one portion of the strip in its

initial open position and another portion in its closed position. Fig. 2 is a section of a trimming in open position, while Fig. 3 is a corresponding view showing a wire slidingly mounted within the article and Fig. 4 is a 50 corresponding view showing the fold in closed position, the wire being shown in dotted lines. Fig. 5 is a sectional view showing the attaching means concealed by the fold.

In the drawings the strip is marked 1 and the folding portion is 2. There are preferably shown stitches 3 secured to the outer edge of the inside surface of the fold 2 and also to the body portion, these stitches appearing as two parallel rows with the attaching means 4 positioned intermediate said rows of stitching. There is preferably shown a stiffening substance such as wire 5 which is threaded through the stitches in a way to enable portions of the wire to slide through said stitches. One end of the wire 5 is anchored to the body of the welt at the point 6 (Fig. 1) and the free end 7 of the wire projects beyond the end of the welt or molding to enable the artisan to pull the wire from the serpentine position indicated in Fig. 3 to the substantially straight position indicated in Fig. 4. The wire 5 is preferably a 65 flexible stiffening substance such as that disclosed in Letters Patent No. 1,387,639 and for that reason the friction and tension will stiffen and hold open the folds when the wire is in its normal position as clearly shown in Fig. 3 and will likewise hold the 70 folds closed when the wire is drawn or pulled taut into its final position shown in Fig. 4.

After the attaching devices 4 have been applied to the welt to secure same to a body of a motor car or any other article the artisan can readily manipulate the parts so as to pull the member 5 to a position such that the fold 2 will be brought into its final closed position and as indicated in Fig. 1 this may be by a progressive movement, first closing one 75

portion of the welt thereby bringing the member into a substantially straight position as indicated at left side of Fig. 1, which will thereby reduce the friction and strain between the serpentine wire 5 and the foldable portions which would otherwise hold the folds in open position enabling the other portions of the welt to be closed. It is apparent that after the attaching devices 4 have been concealed throughout the article, then the free 10 end of the wire can be anchored, thereby locking the fold securely in its closed position.

Without further analysis, the foregoing will so fully reveal the gist of this invention that others can, by applying current knowledge, readily adapt it for various utilizations by retaining one or more of the features that, from the standpoint of the prior art, fairly constitute essential characteristics 20 of either the generic or specific aspects of this invention and, therefore such adaptations should be, and are intended to be, comprehended within the meaning and range of equivalency of the following claims.

Having thus revealed this invention, I claim as new and desire to secure the following combinations and elements, or equivalents thereof, by Letters Patent of United 30 States:

1. In a welt the combination of a bead portion and a nail concealing portion connected thereto by a nail receiving strip, a flexible stiffening member normally in position for holding said portions separated, means for attaching said member to said portions and permitting said member to be pulled taut and straightened whereby said concealing portion is folded over on to said strip.

2. As an article of manufacture, a welt comprising a nail concealing portion hingedly connected to a nail receiving strip, a flexible serpentine stiffening member normally holding said portions separated, attaching devices for said member permitting portions thereof to be pulled along said strip into a straightened position whereby said concealing portion will be folded upon said strip.

3. In a welt the combination of a flat strip comprising a nail receiving portion and a nail concealing portion, said last mentioned portion being capable of being folded over and on to said first mentioned portion, with a flexible serpentine member normally stiffening said concealing portion, means for slidingly mounting portions of said member upon said strip whereby said member may be pulled taut and straightened thereby simultaneously causing said concealing portion to be folded over said receiving portion.

4. In a welt the combination of a flat strip comprising a bead portion, a nail receiving portion and a nail concealing portion con-

nected together, a flexible re-enforcing member normally holding said portions extended into open position, attaching devices for loosely holding portions of said member on said strip, permitting said member to be pulled taut into straightened position for forcing said concealing portion upon said strip.

In witness whereof, I have hereunto subscribed my name.

AUGUST W. SCHMID.
